UNITED STATES PATENT OFFICE.

FRANK KAUFMAN, OF DAYTON, OHIO, ASSIGNOR, BY MESNE ASSIGNMENTS, TO THE WEST SUPPLY COMPANY, OF COLUMBUS, OHIO, A CORPORATION OF OHIO.

ROLL-PAPER HOLDER AND CUTTER.

No. 826,666.

Specification of Letters Patent.

Patented July 24, 1906.

Application filed August 31, 1901. Renewed February 6, 1906. Serial No. 299,744.

To all whom it may concern:

Be it known that I, FRANK KAUFMAN, a citizen of the United States of America, residing and having my post-office address at 5 Dayton, in the county of Montgomery and State of Ohio, have invented a certain new and useful Roll-Paper Holder and Cutter; and I hereby declare that the following is a clear, full, and exact description thereof, reference being had to the accompanying drawings, in which like characters refer to like parts.

My present invention relates to roll-paper holders and cutters; and it particularly relates to the constructions, arrangements, and 15 combinations of the various parts, as well as the apparatus as a whole, all of which will be hereinafter more fully described, as well as clearly specified in the appended claims.

In the drawings illustrating the best form 20 of apparatus to me now known for embodying my invention, Figure 1 is a perspective view thereof; Fig. 2, a sectional elevation thereof substantially on line *x* *x* of Fig. 1. Figs. 3, 4, 5, and 6 are perspective views illustrating details of construction thereof. Fig. 25 7 is a bottom plan view of the part shown in Fig. 5. Fig. 8 is a front elevation showing the manner in which the apparatus may be coupled together to form pyramids for supporting, usually, rolls of paper of different widths. Fig. 9 is an end elevation view showing a 30 different knife. Fig. 10 is a plan view of said different knife, and Fig. 11 is a sectional view of a portion of projections 30 of members 11.

In said drawings, 10 represents one or more rods extending across the top of the apparatus and secured at each of its or their opposite ends to a member 11, provided with 35 one or more pyramidal recesses 12 in the lower face thereof. The lower end of each of said members 11 is provided with a slot through which is adapted to be passed a bolt 13, Fig. 2, securing the foot 41 to the bottom of each of said members 11. From the adjacent faces of the vertical members of the frame thus formed project bearing-cups 15 for receiving and supporting the opposite ends of the paper-roll spindle 16. The knife 40 17 or 18 for cutting the paper is guided by this frame to maintain its position upon the paper-roll, the knives 17 and 18 being re-

spectively hinged to and sliding upon said frame.

In order to avoid the expense of and necessity for machine-work upon or coring bearing-openings in the arms of knife 17, I have so formed the ends of said arms that they may be cast without cores and with a bearing therein which hooks upon said frame. 55 When said frame is formed of two rods 10, said arms of knife 17 are passed under the near rod 10 and hooked over the far rods 10 and cannot be unhooked therefrom until the paper-roll and its spindle 16 are removed 60 and said knife 17 moved on its fulcrum past the bearings 15.

Both the knives 17 and 18 may be inserted to project from and cut paper upon either side of the frame, as may be most convenient 70 to the operator.

In the precise embodiment of my invention shown in the drawings the members 11 extend from the bottom to just above the center of the vertical members of the frame or 75 rods 10, which rods are square in cross-section and bent so that their diagonally opposite or inner and outer corners lie in the same plane. Said members 11 are each provided with V-shaped vertical recesses 19 and 20, 80 Fig. 5, near their upper and lower ends, which fit against the vertical portions of rods 10. The lower ends of rods 10 are clamped to said recesses 19 of members 11 by clips 21, Figs. 2, 4, and 8, having V-shaped recesses 22 registering with said recesses 19, and bolts or rivets 23 bind clips 21 to said members 11. The rods 10 are clamped in said recesses 20 by bolts or rivets 24, passing through openings in members 11, and bearing-cups 15, having V- 85 shaped recesses 25, Fig. 3, registering with said recesses 20.

For the purpose of assisting the bolts or rivets 24 in holding the bearing-cups 15 in position when the paper-roll is in position I 95 provide projections 26, Figs. 2, 5, and 8, from members 11 upon which said cups 15 rest. This, however, is merely a precautionary measure, adding strength to the device, as well as facilitating the assembling by positioning said cups 15.

Each of the members 11 are provided intermediate their ends with a projection 30, Figs. 1, 5, and 8, having a cavity on their in-

ner sides and lateral strengthening-ribs 31. Said projections 30 have broad outer faces projecting beyond any other portion of the end of the device, so that a bolt or other securing means may be passed through openings 32 in said projections 30 to secure two or more of the apparatuses end to end, and thus form what is termed in this art a "flat pyramid," as shown in the two lower cutters 5 in Fig. 8, while in building what is termed a "high pyramid"—that is, one cutter upon the top of another—the bolts 13 are removed from the feet of the cutter to be mounted upon the top of another, and said feet separated from said cutter. Then places said cutter upon the top of one or more lower cutters, as shown in Fig. 8, with the V-shaped pyramiding recesses 12 in the bottoms of said member 11 fitting upon the horizontal portions of the 10 rods 10, where said upper cutter is secured by substituting a clamp 21 for the feet which were removed from said cutter and bolting said clamps to the bottom of member 11 by the same bolts 13 which secured the feet thereto, the V-shaped recesses 22 in said members 21 bearing against said rods 10. In this manner any number of devices embodying my invention may be secured together in any of the many combinations or arrangements of the different sizes of cutters which are desirable to be pyramided.

The apparatus embodying my invention may be pyramided upon the top or tops of any of the cutters now upon the market by 35 removing the feet from the bottom of members 11 and bolting the straight bottoms of said members 11 upon the top cross bar or bars of the said other cutters, said bolt passing through slot 40, Figs. 5 and 7, in the bottoms of said members 11 in the same manner that said bolts are employed to secure the feet thereto.

The feet 41 are provided on opposite sides with lugs 42 and 43 and bolt-hole 44 intermediate said lugs, the lug 42 fitting into the mouth of said slot 40 in the bottom of member 11 and said lug 43 fitting into a lateral recess 45 in the opposite side of each of the members 11 in order to prevent said feet 41 from being twisted when secured each by one bolt 13, which for reasons of economy is all that I desire to employ in commercially practicing my invention. This same purpose is further accomplished by lugs 46 projecting from the upper surface of each of the feet 41 and on opposite sides of the lower end of members 11, so that lower end of members 11 is adapted to fit between said lugs 46. A further purpose of said lug 43 is to prevent 60 the removal of feet 41 should the bolt 13 become loosened by use, which removal could otherwise be accomplished by the relative movement of said feet 41 and members 11 to displace bolt 13 from their slot 40 in said members 11.

As further illustrating the advantages and commercial adaptability and utility of my present invention, and more particularly of the frame thereof when constructed of two rods 10, I have introduced Figs. 9 and 10, 70 showing the knife 18 riding upon the top of the roll of paper and maintained in such position by projections 50 upon the opposite ends thereof extending between and being guided by the vertical portion of the two rods 10, 75 said knife 18 being formed of substantially flat material.

By reason of unobstructed space between the horizontal portions of rods 10 said knife 18 may as well be removed from the top of the 80 roll of paper through said space between the horizontal portions of said rods 10, the rear edge of the knife 18 being raised first into said space in thus removing said knife. Said knife 18 may thus be removed for the purpose of putting in a new roll of paper or for 85 other purposes and replaced after the roll has been inserted, which obviates the necessity of holding the knife up with one hand while the roll of paper is inserted with the other, as 90 must be done with other makes of cutters.

Having thus described my invention so fully and clearly that others skilled in the art may make and use the same when this exclusive grant shall cease to operate, what I 95 claim, and desire to secure by Letters Patent, is—

1. In a roll-paper holder and cutter, the combination of a frame consisting of a rod bent substantially U-shaped, a bearing member secured to each of the vertical arms thereof and a foot secured to each of the lower ends of said vertical arms, and overlapping portions on one of said two last-named members for projecting beyond the adjacent face of 100 the other, said feet being substantially flat and projecting from opposite sides of said vertical arms at right angles to the horizontal member of said frame, means movably mounted in said frame for bearing against 105 the paper-roll parallel with its loose end, and a concave recess in the bottom of and extending longitudinally of said frame, whereby one frame may be mounted upon another with said recesses fitting the horizontal portion of the rod of the lower frame, substantially as specified.

2. In a roll-paper holder and cutter, the combination of a frame consisting of a substantially square rod bent substantially U-shaped and having one of its corners substantially central upon its outer edge, open-topped bearing-cups independent of said rod and secured one to each of the vertical portions of said frame and projecting from the 125 adjacent faces of said vertical portions of said frame; substantially rectangular ribbed feet removably secured intermediate their ends to the ends of said vertical portions of said frame, coöoperating overlapping portions in 130

termmediate said feet and the ends of said portions of said frame to which they are secured, a knife having arms near opposite ends, and means for fulcruming said arms to and near the top of said frame and causing said knife to bear against the periphery of the paper-roll adapted to be carried in said bearing-cups, substantially as specified.

3. In a roll-paper holder and cutter, the combination of an angular continuous rod having its ends bent downward at substantially right angles, said bends being relatively short and said bent ends being substantially of equal length, the portion of said rod intermediate said bends being substantially straight, an open-topped bearing-cup secured to each vertical portion of said rod substantially midway its height, and a recessed portion independent of and on the end of each of said vertical portions of said rod, said portions extending to and connecting with said bearing-cups and said recesses in said portions extending through the lower face of each of said portions and being parallel with and vertically below the horizontal portion of said rod, whereby a plurality of frames formed of said bent rods may be set one on top of each other with said recesses fitting the horizontal portion of the angular rod of the next lower frame, substantially as specified.

4. In a roll-paper holder, the combination of a frame consisting of standards having supporting portions and means for connecting said standards together, bearing portions for the paper-roll, and supporting means independent of said standards and extending from the supporting portions of said standards to said bearing portions for supporting said bearing portions, substantially as specified.

5. In a roll-paper holder, the combination of a frame consisting of standards and means for connecting them together, bearing members for the paper-roll, supporting means independent of said standards and extending from the supporting portions of said standards to said bearing members, and means for securing said bearing members to said supporting means with said standards intermediate them, substantially as specified.

6. In a roll-paper holder, the combination of a frame consisting of standards and means for supporting and connecting them together, bearing members for the paper-roll, an independent supporting member adjacent each of said standards and extending from said supporting means to each of said bearing members, an opening through each of said supporting and bearing members, and a bolt or rivet passing through each of said supporting and bearing members for securing said members together and to said standards, substantially as specified.

7. In a roll-paper holder, the combination of a frame including standards, and feet for

supporting said frame; bearing members for the paper-roll, an independent member adjacent each of said standards and extending from said feet to said bearing members, a recess intermediate each of said supporting and bearing members in which recesses said standards pass, and means for securing each of said supporting and bearing members together with said standards clamped in said recesses, substantially as specified.

8. In a roll-paper holder, the combination of a frame including standards, and feet for supporting said frame; bearing members for the paper-roll, an independent member adjacent each of said standards and extending from said feet to said bearing members, recesses in the adjacent faces of each of said supporting and bearing members in which recesses said standards pass, and a single means for securing each of said supporting and bearing members together and clamping said standards in said recesses, substantially as specified.

9. The combination of a rod bent substantially U-shaped a bearing member secured to each of the vertical members thereof, a member secured to the lower ends of each of the vertical members of the rod, a recess in and extending through the lower face of each of said last-named members, said recesses being vertically below the horizontal portion of said rod, and a separate member secured to each of said last-named members, substantially as specified.

10. The combination of a rod bent substantially U-shaped, a bearing member secured to each of the vertical portions thereof, a member secured to the lower end of each of the vertical portions of said rod, said member having a projection extending outward beyond any interfering part of the apparatus, a slot in said projection of said member for enabling one or more of said devices to be secured end to end, a recess in the bottom face of said last-named member, substantially as specified.

11. The combination of a plurality of rods bent substantially U-shaped and arranged substantially parallel to each other with an unobstructed space between them, a bearing member secured to each of the vertical sides of the frame formed by said rods, a member secured to the lower end of each of the vertical portions of said frame, a corresponding plurality of recesses in the bottom face of each of said last-named members, said bearing member being adapted to support a roll of paper, and a knife movably mounted in said frame by projections of said knife extending into said unobstructed space, and said knife being adapted to rest upon the roll of paper, substantially as specified.

12. In a paper holder and cutter, the combination of a frame provided with supports for the paper, a knife having arms and rest-

ing upon the paper, hooks on the under side of said arms substantially equidistant from the severing edge of said knife, a frame-rod adapted to coöperate with said hooks, a second rod adapted to prevent the disengagement of said hooked arms when the paper-supply is adequate, and a space between said rods greater than the height of the hooked portions of said knife-arms for permitting the disengagement of said arms and rod when the paper-supply is inadequate, substantially as specified.

13. The combination of two rods 10 bent substantially U-shaped, a member 11 between each vertical member thereof and provided with recesses 19 and 20 engaging said rods, a bearing member 15 secured to each of said members 11 and having recesses 25 engaging said rods at a point substantially opposite said recesses 20; a clip 21 having recesses 22 engaging said rods substantially opposite said recesses 19, said clips 21 being secured to said members 11, and a separate member removably secured to the bottom of each of said members 11, substantially as specified.

14. In a paper-cutter, the combination of a rod substantially square in cross-section and bent substantially U-shaped with two of its diagonally opposite corners occupying the same vertical plane, with means for supporting the roll of paper therein and securing feet thereto, said means having recesses fitting said rod, and a knife movably mounted upon said rod to engage the paper, substantially as specified.

15. In a paper-holder, the combination of a frame including upright separated rods on opposite sides, a member and a bearing portion at each end of said frame, recesses intermediate said members and bearing portions adapted to be occupied by said rods, and means intermediate said rods for securing said members and bearing portions to said rods, substantially as specified.

16. In a paper-holder, the combination of a plurality of separated rods bent substantially U-shaped, a relatively long member upon each of the upright sides of the frame formed by said rods, said members bearing near opposite ends against one side of said rods, a bearing-cup upon each end of said frame and bearing upon the side of said rods opposite said members, recesses in said bearing-cups for said rods, a clip for securing each of said members near their opposite ends to said rods, feet upon said members remote from said bearing-cups, and a bolt or rivet passing through each of said cups and members and each of said clips and members intermediate said rods, for securing said parts together and to said rods, substantially as specified.

17. A paper-cutter frame comprising two substantially parallel rods bent substan-

tially U-shaped, bearing members upon the opposite sides of the vertical portions of said rods, feet upon the lower ends of said vertical portions of said rods, and means for securing said rods, bearing members and feet together, said rods having a vertically-unobstructed space intermediate them, substantially as specified.

18. In a paper-cutter, the combination of a frame, bearing members secured thereto each comprising a substantially U-shaped cup 15 having a back wall provided with recesses 25 therein near opposite sides, adapted to receive the ends of the frame-rods, substantially as specified.

19. The combination of a plurality of frames each having on opposite ends an abutting projection extending beyond any interfering portion of said frames, a slot in each of said projections, and a bolt passing through each of said slots in said abutting projections for securing said frames together, substantially as specified.

20. In a roll-paper holder and cutter, the combination of a plurality of frames, a recess in the bottom part of each of said frames, a portion of the top of each of said frames being adapted to fit said recesses, the top frame setting upon the lower frame with said recess in its bottom part fitting said portion on the top of said lower frame, and one or more clips removably secured to said upper frame and confining said portion of said lower frame in said recess in the bottom of said upper frame and between said upper frame and said clip, substantially as specified.

21. In a roll-paper holder and cutter, the combination of a plurality of frames, a plurality of separated engaging faces in a different plane from the bottom part of each of said frames, a corresponding plurality of separated portions of the top of each of said frames adapted to engage said faces, the top frame setting upon the lower frame with said faces in its bottom part fitting said portions on the top of said lower frame, said faces and separated portions of different frames being vertically separable, and means removably secured to one of said frames and engaging with another of said frames for removably maintaining the engagement of said faces and portions, substantially as specified.

22. In a roll-paper holder and cutter, the combination of a plurality of frames; a projection on each of the opposite ends of said frames extending beyond any interfering portion of said frames, a slot in each of said projections, means passing through said slots in the abutting projections of said frames for securing said frames end to end, a recess in the bottom part of each of said frames, a portion on the top of each of said frames adapted to fit each of said recesses, and one or more clips adapted to clamp any of said

frames upon the top of one or more of said frames with said recess in its bottom fitting said top portion of the lower frame or frames, substantially as specified.

5 23. In a roll-paper holder and cutter, the combination of a plurality of frames, a projection upon each of the opposite ends of said frames extending beyond any interfering portion of said frames, a slot in each of said projections, means passing through said slots in the adjacent ends of said projections for securing said frames end to end; a plurality of recesses in the bottom part of each of said frames, a corresponding plurality of portions 10 upon the top of each of said frames adapted to fit said recesses, and one or more clips adapted to clamp any of said frames upon the top of one or more of said frames with said recesses in its bottom part fitting said top

portions of the lower frame or frames, substantially as specified. 20

24. In a paper-cutter, the combination of a frame, recesses 45 near opposite ends of the bottom thereof, a removable foot upon each side of the lower end of said frame, a projection 43 upon each of said feet adapted to fit said recesses 45, and bolts passing through the lower ends of said frame and said feet with a portion of said frame intermediate said bolts and recesses 45, substantially as 25 30 specified.

In witness whereof I have hereunto set my hand this 1st day of April, 1901.

FRANK KAUFMAN.
